BUCKLE FRAME

Holman D. White, Hamden, Conn., assignor to
Parva Products Company, Chicago, Ill., a cor-
poration of Delaware

Application April 24, 1948, Serial No. 145,953

Term of patent 7 years

(Cl. D17—1)

To all whom it may concern:

Be it known that I, Holman D. White, a citizen of the United States, residing at Hamden, in the county of New Haven and State of Connecticut, have invented a new, original, and ornamental Design for a Buckle Frame, of which the following is a specification, reference being had to the accompanying drawing, forming a part thereof, in which:

Fig. 1 is a plan view of a buckle frame embodying my new design;

Fig. 2 is a side elevational view of the buckle frame shown in Fig. 1;

Fig. 3 is an end view thereof; and

Fig. 4 is a perspective view on a somewhat larger scale of the buckle frame shown in Figs. 1, 2 and 3.

I claim:

The ornamental design for a buckle frame, substantially as shown.

HOLMAN D. WHITE.
